EARL S. BJONERUD, OF CALMAR, IOWA.

LETTER-OPENER.

1,308,218.

Specification of Letters Patent.

Patented July 1, 1919.

Application filed January 23, 1918. Serial No. 213,378.

To all whom it may concern:

Be it known that I, EARL S. BJONERUD, a citizen of the United States, residing at Calmar, in the county of Winneshiek and 5 State of Iowa, have invented certain new and useful Improvements in Letter-Openers, of which the following is a specification.

This invention relates to an improved letter opener which may be connected with the 10 edge portion of a desk and the principal object of the invention is to provide an improved type of letter engaging jaw and body portion and an improved type of cutting knife and bracket for mounting the cutting 15 knife.

Another object of the invention is to so construct the bracket for the cutting knife that it may be vertically adjusted to cause the cutting knife to enter the body portion 20 the desired extent to cut the envelop as the envelop is drawn through the trough of the body portion between the jaws mounted therein.

Another object of the invention is to so 25 construct this letter opener that the cutting blade may be removed when it is desired to sharpen the blade.

Another object of the invention is to so 30 construct this letter opener that it will be simple in construction but very efficient in operation and easy to assemble or take apart when necessary.

This invention is illustrated in the accompanying drawings, wherein:—

35 Figure 1 is a view showing the improved letter opener in side elevation,

Fig. 2 is a top plan view of the improved letter opener,

Fig. 3 is a vertical sectional view through 40 the improved letter opener, and

Fig. 4 is a perspective view of the blade carrying bracket with the blade in place.

The body portion or trough 10 has its inner wall provided with a flange 11 through 45 which screws or other fasteners 12 may be passed to connect this body portion with the edge portion of the desk 13. The outer wall has one corner portion bent to provide a guiding lip 14 making it easy to insert a 50 letter to be opened. The clamping jaws 15 which will be formed of resilient sheet metal are secured in the trough by the rivets or 55 other fasteners 16 and when in use, the letter will be placed between these jaws and then drawn longitudinally of the trough so that the blade 17 will engage the closure flap

of the letter envelop and cut the envelop thus permitting the letter within the envelop to be removed. This blade is secured 60 between the clamping jaws 18 of the bracket 19, the jaws 18 being releasably connected with the bracket by the fastener screws 20. The bracket 19 is provided with a stem 21 which extends upwardly and through the eye 22 carried by the outer wall of the 65 trough or body 10 and has its upper end portion threaded to receive the adjusting and securing nut 23 which nut when tightened will draw the bracket upwardly against the action of the spring 24 and move the 70 blade 17 into the bottom of the trough the desired distance. It will thus be seen that this blade can be held to extend into the trough the desired amount to properly engage the envelop and sever the flap from 75 the body portion of the envelop. When it is desired to sharpen the blade, it is simply necessary to release the screw 20 and the blade can then be drawn outwardly from between the jaws 18. The nut 23 will of 80 course, be removed to release the bracket, thus detaching the bracket from the body portion of the letter opener and permitting the blade to be easily removed and then put back in place. It will thus be seen that there 85 has been provided a letter opener which will be of simple construction and very efficient in operation.

What is claimed is:—

1. A letter opener comprising a trough, 90 gripping jaws in the trough in operative relation to an opening formed therein, a bracket connected with the trough, and a cutting blade carried by the bracket and extending into the trough through the opening thereof between the gripping jaws within the trough.

2. A letter opener comprising a trough, gripping jaws within the trough, a bracket carried by the trough, and a cutting blade 100 carried by the bracket and extending into the trough between the gripping jaws.

3. A letter opener comprising a trough, gripping and guiding jaws within the trough, a bracket carried by the trough, and 105 a cutting blade releasably connected with the bracket and extending into the trough between the jaws.

4. A letter opener comprising a body portion, a carrier connected with the body portion, and a cutting blade carried by the carrier and extending into the body portion. 110

5. A letter opener comprising a body portion, a bracket, an eye carried by the body portion, the bracket being provided with a stem extending through the eye, a spring element upon the stem engaging the eye to yieldably hold the bracket against upward movement, a fastener carried by the stem to engage the eye and move the bracket upwardly when the fastener is tightened, and
- 10 a cutting blade carried by the bracket and moving into and out of the trough as the bracket is vertically adjusted through the medium of the fastener.
6. A letter opener comprising a body, a bracket having a stem, an eye carried by the body with the stem extending through the eye, a spring upon the stem engaging the eye to yieldably hold the bracket against upward movement, a fastener nut upon the upper portion of the stem engaging the eye, gripping jaws connected with said bracket, and a cutting blade positioned between the jaws and extending into the body.
- 15 7. A letter opener comprising a body having a bottom with an opening therein and having an outer side wall and an inner side wall provided with a supporting flange, guiding jaws in the body in operative relation to the opening in the bottom thereof,
- 20

Copies of this patent may be obtained for five cents each, by addressing the "Commissioner of Patents, Washington, D. C."

an eye extending from the outer wall of the 30 body, a bracket having a stem extending through the eye, resilient means about the stem and engaging the eye to yieldably hold the bracket against upward movement, a fastener adjustable upon the upper portion 35 of the stem engaging the eye, gripping jaws carried by the bracket, and a blade between the gripping jaws of the bracket extending into the body through the opening in the bottom thereof in operative relation to the 40 guiding jaws within the body.

8. A letter opener comprising a trough, guiding jaws in the trough, and a cutting knife extending above the bottom of the trough in operative relation to the guiding 45 jaws.

9. A letter opener comprising a trough, a carrier connected with the trough, and a cutting blade carried by the carrier and extending into the trough above the bottom 50 thereof.

In testimony whereof I affix my signature in presence of two witnesses.

EARL S. BJONERUD.
